Term of patent 14 years

Int. Cl. D12—14

U.S. Cl. D90—20

Fig. 1

FIG. 2

FIG. 1 is a perspective view of a tire of my new design; and

FIG. 2 is a fragmentary sectional view through the tire taken on line 2-2 of FIG. 1.

It is to be understood that the tread pattern shown is continuous throughout the circumference of the tire. The side opposite that shown in FIGURE 1 is a mirror image thereof.

The dominant features of my design reside in those portions shown in solid lines.

I claim:

The ornamental design for a tire, substantially as shown and described.
